UNITED STATES PATENT OFFICE

PETER S. SINCLAIR, OF HOLYOKE, MASSACHUSETTS, ASSIGNOR TO HOLYOKE HEATER COMPANY, OF HOLYOKE, MASSACHUSETTS, A CORPORATION OF MASSACHUSETTS

AIR INLET DEVICE FOR OIL BURNERS

Application filed November 27, 1926. Serial No. 151,076.

This invention relates to improvements in air inlet devices for oil burners of the type of construction in which the water heating coils are located within an inclosing casing, which 5 inclosing casing serves as a combustion chamber in which a blue flame is produced, and to carry off the heated products of combustion.

The present invention is an improvement on the construction shown, described, and 10 claimed in my prior joint Letters Patent of the United States granted to George C. Gill, Peter S. Sinclair, and Patrick J. Moakler, #1,246,813, dated November 13, 1917. In this patent is shown a removable ring which 15 is located between the burner and the inclosing casing and having an air tight joint on the casing and burner respectively. This ring is formed with a series of openings to permit the requisite volume of external air to enter 20 the casing from below and pass upward into contact with the upper part of the burner. The present invention has for an object to provide an air inlet device in which the flow is substantially unbroken and uniform and 25 without its being broken up into small streams of air which is the case with a perforated ring.

In the present invention, this ring is omitted and in its place there is provided an 30 annular flange which is formed as an integral part of the back casing and front casing or door respectively. These flanges are each formed with a plurality of spaced lugs or projections, which lugs are designed to engage 35 the outer surface of a collar or ring of the burner, whereby an annular space between the collar or ring and casing is provided to permit the external air to flow as a solid stream upward into the inclosing casing and 40 above the burner.

The invention further comprises a series of lugs located on the interior surface of the collar or ring. These lugs are for the purpose of radially and concentrically spacing 45 this collar from the outside surface of the burner in order to permit the external air to flow upward within the collar and directly into contact with the upper end of the wick portion of the burner and below the usual 50 deflecting plate or flame spreader of the

burner. They also serve the important feature of accurately and concentrically centering the collar relative to the inner surface of the casing. Some of the lugs on this collar are longer and slotted to permit them to pass through openings or spaces which are formed on the flange that is located and attached to the outside of the burner, whereby when the collar is moved downward these longer lugs 55 will pass through these openings in the flange. The slits will then pass onto the flange. This collar or ring can therefore be securely locked to the burner, and, at the same time it is accurately centered and spaced from the outside surface of the burner for producing an annular opening of uniform area which completely surrounds the outer surface of the burner. The other or shorter lugs that do not pass through the openings or slits in the 60 flange are designed to rest directly on the upper surface of the flange thus preventing the collar or ring from tilting relative to the axis of the burner. The collar is therefore accurately positioned or centered both vertically and horizontally on the burner. The 65 annular openings on both the inside and outside of the collar are of uniform area throughout their length.

It is also to be noted that in the elimination of the removable perforated ring employed in my former joint Patent No. 1,246,813 and in the substitution or utilization of the integral flange having spacing lugs which operate as an air controlling and burner centering member that a very much 70 more simple structure is obtained at materially less cost to manufacture. This also makes a positive contact with the collar or ring which prevents tilting of the same, which tilting consequently would cause an 75 unequal flow of air resulting in an uneven flame and imperfect combustion.

In the elimination of the removable perforated ring or collar shown in my prior joint patent and in the substitution of the integral flange having air spacing lugs on the door and back casing, together with the interlocking collar or ring member on the burner, a simpler structure is obtained and a positive engagement made between the burner collar 80

55

60

80

85

90

95

100

or ring and the casing. This construction when assembled provides a rigid combination unit of the casing, the flange, the collar, and the burner all arranged in concentric alignment.

5 The interlocking devices of the collar or ring on the flange of the burner avoids or overcomes any tendency of the collar or ring to tilt which would cause the annular air space inside and outside of the collar or ring to be out of concentric alignment.

10 Another object in the utilization of the flange of the outer wick tube is to provide spacing and interlocking devices between the 15 ring or collar of the wick tube in order to have an annular air space between the ring or collar and wick tube. It also provides the annular flange on the front and back casing for 20 obtaining a predetermined amount or quantity of air to form perfect combustion.

25 A more simple structure is obtained at less cost of manufacture by the elimination of the removable perforated ring and the substitution of the integral internal flange with 30 spacing lugs on the door and back casing. This structure in conjunction with the interlocking collar or ring member makes a positive connection between the burner collar or ring and the casing resulting in an even and 35 perfect combustion entirely around the burner and consequently more heat.

I claim that by using the flange and lugs on the door and the back casing, by dispensing with the perforated ring and by pivotally 35 supporting the feed pipe and the burner that the burner can be positioned closer to the heating element, which will obviously heat the water more quickly.

40 I claim that by using the pivotal joint construction to permit the burner to be swung out from the casing when it is necessary to either clean it or to change the wick permits the burner to be positioned nearer to the water heating element in the casing with a 45 more intense heat delivered to the water heating element.

Reference is now made to the drawings and specifications for a full description.

Referring to the drawings:

50 Fig. 1 is a vertical elevational view of the complete oil water heater showing the interior of the inclosing casing with the plurality of spirally arranged coils therein, the oil burner, the integral flange on the interior surface of the burner and door respectively, and the means for pivotally supporting the oil supply receptacle and its feed pipe.

55 Fig. 2 is a sectional plan view considered on the line 2—2 of Fig. 3.

60 Fig. 3 is a vertical sectional view showing the collar or ring and the upper portion of the burner in section illustrating the supporting and locking lugs on the interior of the collar or ring and in engagement with the flange on 65 the burner.

Fig. 4 is a detail plan view of a part of the upper end of the burner and particularly showing the flange on its outer surface with the three slots or openings formed therein.

70 Fig. 5 is a side elevational view of Fig. 4.

Fig. 6 is a plan view of the collar or ring illustrating the locking, supporting, and spacing lugs which are secured on the interior surface of the collar or ring.

75 Fig. 7 is a side elevational view of Fig. 6.

Fig. 8 is a detail view of a portion of the outer part of the burner in section, and illustrating one of the shorter supporting and spacing lugs on the outer surface of the 80 flange of the burner.

Fig. 9 is a view similar to Fig. 8 illustrating one of the longer and slotted locking and spacing lugs and the flange of the burner spaced from the opening in the lugs.

85 Fig. 10 is a perspective view of the collar or ring showing the location of the locking and spacing lugs on its inner surface.

Fig. 11 is a perspective view with the collar removed but illustrating the manner of 90 locking the collar to the flange of the burner.

Fig. 12 is a plan view of the collar or ring showing a modification of the locking lugs.

Fig. 13 is a modification of the burner illustrating the raised ridges or mutilated threads 95 with which the lugs shown in Fig. 15 engage.

Fig. 14 is a detail of one of the raised ridges or mutilated threads.

Fig. 15 is a detail of one of the locking lugs on the ring shown in Fig. 12.

100 Fig. 16 is a detail perspective view illustrating the relation of the lugs of the integral flange in engagement with the collar or ring of the burner for centering the same in the casing.

Fig. 17 is a detail plan view of the flange and its integral lugs and the collar or ring showing the annular air space.

Referring to the drawings in detail:

1 designates the back casing; 2 the front or door part of the casing which is pivotally connected to the back casing as indicated by the hinge construction 3. Located within the inclosing casing are the water heating coils 4, several of which are shown that are connected at their upper end and lower end to the common manifolds 5 and 6. The lower manifold serving for the entrance of the water to be heated which flows upward through the coils 4 to the manifold 5 where the heated water is discharged through the outlet pipe 7. 8 is a top casting or plate which is secured to the back member 1 by means of the bolt construction 9. The lower end of the back casing 1 is formed with a flared or downward and outwardly extending part, indicated at 10 and having the inwardly turned flange 11. Secured to this flange is a plate 12 for supporting the burner 13 and feed pipe 15. 14 is an internally re-

85

cessed lug or projection which is located on the center portion of the plate 12 and is designed for attaching a supporting pipe or pedestal if desired. An oil feed pipe 15 is pivotally connected to the burner plate 12 as indicated by the pin 16, which pin is a part of the lower clamping member 17 in which the feed pipe 15 rests. 18 is the upper clamping member that rests on the upper surface of the feed pipe 15 and is secured to the lower clamping member 17 by means of the screws 19. Attached to the feed pipe 15 is a cylindrical member 20 which supports the removable oil supply can or reservoir 21. The outer end of the feed pipe 15 rests upon the block or foot piece 22 and is releasably retained in place by means of the spring clip 23. The burner 13 is secured to the fuel feed pipe 15 by means of the clamping construction 24, and the block or rest 25. The part indicated at 24, also supplies oil to the burner 13 from the feed pipe 15, as shown at 17 in my prior joint Patent No. 1,246,813, Nov. 13, 1917. The burner 13 is formed with an external flange or rib 26, which rib is designed for supporting and securing the collar or ring 27, a plan view of which is shown in Figs. 6 and 12, a side elevational view in Fig. 7, a perspective view in Fig. 10. Secured to the inner surface 28 of this collar are a series of locking and spacing lugs or projections 29 and 30. The lugs 29 are formed with a slot or cut out portion 31 (see Fig. 9) and with a surface or edge portion 32 which is at right angles to the slot 31. The lugs 30, as shown in Fig. 8, enlarged view, are not formed with slots or openings as are those illustrated in Fig. 9 by the reference numeral 31. These lugs 29 and 30 are each formed with the securing tongues 33 which pass through openings in the collar or ring 27, and then bend over at the outer surface of the collar or ring 27 for securing the same thereto. This construction is clearly shown in Figs. 2, 3, and 7. It will be observed that the lugs 29 are longer than the lugs 30.

The flange 26 is formed with the cut out openings or spaces 34 three of which are shown in Fig. 4. The collar 27 is secured to the flange 26 of the burner by placing it over the upper end of the burner and then pushing it downward as indicated by the arrows 35 in Fig. 11, then, by turning it toward the right or left hand as indicated by the arrows 36. This turning causes the longer and slotted lugs 29 to register with the openings or spaces 34 in the flange of the burner 13.

The next operation is to move the collar or rim 27. The slots 31 will now be opposite the ends 37 of the flange 26, next turn the collar 27. This permits the slots to pass onto or engage with the flange 26 of the burner, whereby the ring or collar 27 is interlocked to the flange 26 of the burner. At the same time, the lower ends 30' of the lugs 30 rest

directly on the upper surface of the flange 26 of the burner. The lugs 29 and 30 also serve the purpose of accurately spacing or centering the collar or ring 27 on the burner 13, whereby a uniform annular air space 38 is provided between the burner 13 and the inner surface of the collar or ring 27. This is shown in Fig. 3. The centering of the collar or ring 27 being accomplished by the contact of the inner vertical edges 32 of the lugs 29 and 30 resting directly against the outer surface of the burner 13. It should be stated that the lower edge 30' of the lugs 30 when they contact with the flange 26 limits the downward movement of the collar or ring 27 and accurately aligns the slits 31 of the lugs 29 with the ends 37 of the flange 26. Also the lugs 30 resting on the flange 26, together with the interlocking of the slits 31 and flange 26 prevents the collar or ring 27 from tipping or becoming inclined.

The space between the inner surface of the ring or collar 27 and the outer surface of the burner 13 is indicated by the reference numeral 38. This space is for permitting the air to pass upward in a solid unbroken stream and directly into contact with the upper edge of the wick 39 of the burner 13.

For the purpose of permitting the external air to pass upward around the outside of the collar or ring 27, a flange 40 is cast as a part of the back casing 1. This flange is formed with the integral spacing and centering lugs 41. The door member is also formed with an integral flange 42 and centering and spacing lugs 43, whereby when the burner 13 and ring or collar 27 is inserted, it will rest against the lugs 41 of the back casing, and, when the door is closed, the lugs 43 will engage or contact with the outer surface of the collar or ring 27 of the burner 13. This construction provides an accurate way of forming a uniform and annular air space 44 around the outside of the collar or ring 27. These lugs further perform the important function of accurately centering the collar or ring 27 in the casing.

This is clearly shown in the plan view in Fig. 2, thus providing the uniform annular air spaces 44 on both the back casing 1 and door 2. The lower sides of these lugs 41 and 43 are inclined as indicated at 41'.

Referring to Figs. 12, 13, 14 and 15. The burner 13 is formed with several struck up inclined parts 45, which in effect are mutilated threads. The notched recesses 46 in the lugs 47 are designed to engage the threads 45 on the collar or ring 27, whereby when the collar or ring 27 is turned, it will be locked, secured, and centered on the burner 13 in the same manner as already described in connection with Figs. 10 and 11.

One of the advantages of the elimination of the perforated ring referred to in the above patent between the casing and burner is that

in practice users often attempt to insert it in an inverted position resulting in poor combustion and in the causing of large quantities of carbon which collects on the coils.

5 Further by the elimination of the removable perforated ring shown in the above patent and the substitution of an integral flange with spacing lugs on the back member and door, a more simple structure is obtained and one that materially saves in the cost of 10 the manufacture of the heater. Also by the elimination of this ring and in the substitution of a flange with spacing lugs it provides substantially an open and unobstructed flow 15 of a solid stream of air into the casing since there is no baffling or retarding or splitting up of the continuous flow of air to the burner.

By reason of the interlocking connection 20 between the collar or ring and the flange and spacing lugs of the burner, the collar or ring is accurately centered, and, the area of the 25 annular opening is uniform throughout its length thus producing better combustion and a more even and intense heat.

25 It will be seen, therefore that I have provided a very accurate way of permitting the external air to flow upward within the collar 27 and also outside of this collar in substantially an unbroken stream. This construction produces an even distribution of 30 the air to the wick and produces also a blue flame which signifies or indicates complete combustion within the inclosing casing and directly below the water heating coils 4.

35 The flange 26 in Fig. 13 operates to accurately center the collar or ring 27 since the lower end 47 engage the same when the collar or ring is turned to firmly secure it on the burner.

40 An important feature of my present invention is that the burner 13 may be placed in a position relative to the heating coils 4 so that the largest number of heat units may be utilized, and, consequently less fuel required 45 to heat a given quantity of water, at a given temperature in a specified time. The perforated ring of my joint prior patent does not permit of the location of the burner in the best heating position. This advantageous 50 water heating position of the burner is accomplished by means of the structure herein described.

Another important feature is that the burner can be properly cleaned and the wick 55 easily changed when swung outward away from the enclosing casing. This feature is obtained by means of the two piece integral flanges 40 and 42 on the casing and door respectively. The one piece perforated ring 60 of said patent will not permit the removal of the spreader part of the burner for cleaning purposes.

What I claim is:

1. An oil water heater comprising in 65 combination, an inclosing casing, water heating

coils therein, an oil burner located within the casing, a removable collar or ring like member on the burner, spacing and centering means on the casing which engage the collar or ring on the burner to provide a concentric and annular air space for causing a predetermined and substantially an unbroken flow of air around the outside of the collar or ring and upward into the casing.

2. In a water heater, the combination with 70 an enclosing casing formed as a back member and front or door member, a water heating element in the casing, an oil burner, a removable collar or ring on the burner, co-operating lug means on the back and door members which engage and center the said collar and provide an annular air space between 75 the casing and collar or ring whereby a predetermined quantity of substantially unbroken air will flow through the said 80 space.

3. In an oil water heater, the combination with 85 an enclosing casing formed as a back member and a front or door member, a water heating element in the casing, an oil burner, a removable collar or ring on the burner, 90 co-operating projecting lug means on the back and door members which engage the removable collar for centering the collar and for providing an annular air space between 95 the casing and collar or ring.

4. An oil water heater comprising in combination, an enclosing casing, a water heating member therein, an oil burner, a collar or ring on the burner, an integral inwardly 100 extending flange on the casing provided with inwardly projecting spacing lugs, which spacing lugs engage the collar on the burner for centering the burner in the casing and for forming a positive annular air passage 105 way around the collar, whereby substantially a continuous and unbroken stream of air will enter the enclosing casing.

5. In an oil burner for oil water heaters, 110 an annular flange on the burner which flange is formed with openings or spaces therein, a collar or ring member engaging the burner and flange, means on the collar or ring which passes vertically through the openings or 115 spaces of the annular flange for locking the collar to the burner when the collar is rotated, said locking means also operating to accurately center the collar on the burner and to provide a positively uniform and concentric annular air space between the collar and 120 the burner.

6. In combination, in an oil burner, an annular flange on the burner, which flange is formed with openings or spaces cut therein, a collar or ring, slotted lugs on the collar which are designed to pass vertically through the openings in the flange, and, when the collar is turned, the slots of the lugs and flange will be interlocked said lugs also engaging 125 the burner for accurately and concentrically 130

- centering the collar or ring relative to the burner for providing an annular air space between the collar or ring and burner of a definite or positive area.
5. 7. In combination, in an oil burner, an annular flange on the burner, which flange is formed with openings or spaces cut therein, a removable combustion collar or ring, slotted lugs on the collar or ring which are designed to pass vertically through the openings in the flange, and, when the collar or ring is turned, the slots of the lugs and flange will be interlocked, said lugs also engaging the burner for accurately centering the collar or ring relative to the burner for providing an annular air space of definite or positive area between the collar or ring and the burner, and other lugs on the collar which normally rest upon the flange.
10. 8. In an oil water heater, the combination with an enclosing casing which serves as the combustion chamber water heating coils in the casing, an oil burner whose upper end is located in the casing and below the coils, a collar or ring on the burner, means on the casing which engages the collar for providing an annular air inlet space between the outside of the collar or ring and the casing, means on the inside of the collar or ring which contacts with the burner for centering the collar or ring on the burner and for providing a free and substantially an unbroken and predetermined air space between the collar or ring and the burner, the latter means having interlocking connection with the burner for retaining it in place on the burner.
15. 9. An oil water heater comprising, in combination, an inclosing casing, a water heating element therein, an oil burner in the casing, a collar or ring like member on the burner, spacing and burner centering means on the casing engaging the collar or ring on the burner to provide a positive or definite annular air space for causing a predetermined and substantially unbroken flow of air around the collar or ring and upward into the casing, said spacing and centering means comprising a flange on the casing and wedge shaped lugs on the flange which engage the collar or ring.
20. 10. The combination in a water heater, an oil burner, an enclosing casing, water heating coils in the casing, devices on the casing which engage the burner for centering the burner in the casing for providing a positive annular and substantially an unbroken air space around the burner.
25. 11. The combination, in a water heater, a casing, an oil burner therein, a rib on the burner, a spacing ring between the burner and casing, a water heating member in the casing, a flange on the casing having inwardly extending lug devices which engage the spacing ring for providing substantially a solid or unbroken supply of air adjacent the inner surface of the casing, inwardly projecting bracket devices on the spacing ring which engage the burner for providing substantially a second unbroken supply of air adjacent the burner proper, the said ring member serving to separate the two unbroken supplies of air, the inwardly projecting lug means on the ring having notches which engage the rib on the burner for interlocking the ring member to the burner, and which inwardly extending lug devices on the flange engage the ring for centering the burner and for preventing its becoming displaced or moved into an inclined position.
30. 12. In an oil water heater, the combination, an enclosing casing, water heating elements in the casing, an oil burner and oil feed pipe for the oil burner on which the burner is mounted, a base plate attached to the casing for pivotally supporting the burner on the base plate which comprises a perforated part on the base plate, a lower oil feed pipe clamping member having a recess to receive the feed pipe and a part which extends through the perforated part of the base plate, an upper oil feed pipe clamping member which rests upon the oil feed pipe, means for securing the clamps together, and means for detachably retaining the oil feed pipe and the burner on the base plate to permit the burner to be swung into and out of the casing.
35. 13. In an oil water heater, a base plate, an oil burner an oil feed pipe connected to the burner, means for pivotally supporting the burner on the base plate comprising a pair of recessed clamps for receiving the oil feed pipe on which the burner is placed, one of the clamps having a projection located in an opening in the base plate, and a spring catch on the base plate for retaining the feed pipe on the burner in its operative position.
40. 14. An oil burner for water heaters having in combination with an enclosing casing, a removable collar or ring on the burner, means for detachably securing the collar or ring on the burner comprising a rib on the burner having openings, notched lugs on the collar or ring adapted to extend through the openings of the rib to position the notches for engagement with the rib, whereby when the collar or ring is rotated it is connected to the burner and centered thereon, as described.
45. 15. In combination in a water heating apparatus, a casing, a water heating member therein, an oil burner having an outer wick enclosing shell, devices for pivotally attaching the burner to the casing, devices on the casing for concentrically centering the burner in the casing and for permitting a predetermined rate of flow of air between the burner and casing to the burner, a collar device on the burner, spacing members on the collar which engage the wick enclosing shell for permitting a predetermined rate of flow of air to the burner between the outer wick en-

closing shell of the burner and the collar device, whereby a blue flame is produced.

16. In a device of the character described, a water heating element, a casing enclosing the water heating element and forming a flue, a burner supporting part on the casing, an oil supply tank, a pipe pivotally connected to said supporting part and communicating with the oil supply tank, a burner on the pipe, means for supplying oil to the burner from the pipe, the burner being manually movable with the pipe into a position under and away from the lower end of the water heating element.

17. In an oil water heating apparatus, the combination with an enclosing casing, a door forming a part of the casing, a water heating member in the casing, an oil burner, a spacing ring, an oil feed pipe for the burner, means for pivotally attaching the burner to the said casing to permit the burner to be swung out when the door is opened, lug means on the casing for engaging the spacing ring for centering the burner in the casing and for providing a uniform supply or flow of air adjacent the upper or wick edge of the burner, a removable flame spreader for the burner, the construction and arrangement being such that the burner is positioned by said lug and ring means relative to the water heating member so as to impart the maximum heating effect to the water heating member, and, also to permit the flame spreader of the burner to be removed, when the burner is swung outward and away from the enclosing casing.

PETER S. SINCLAIR.
